US00D513197S

(12) **United States Design Patent** (10) Patent No.: **US D513,197 S**
(45) Date of Patent: **** Dec. 27, 2005**

(54) **WIND DIRECTION INDICATOR**

(76) Inventor: **Bob Damberger**, P.O. Box 57,
Donaldalda, Alberta, T0B 1H0 (CA)

(**) Term: **14 Years**

(21) Appl. No.: **29/218,137**

(22) Filed: **Nov. 29, 2004**

(30) **Foreign Application Priority Data**

Jun. 2, 2004 (CA) 107187

(51) LOC (6) Cl. **10-04**

(52) U.S. Cl. **D10/59**

(58) Field of Search D10/59; D15/1-2;
73/170.05-170.11, 178 R; 290/44, 55; 446/217-218,
